ROBERT JENNINGS AND JAMES A. MARSHALL, OF BORDENTOWN
NEW JERSEY.

Letters Patent No. 61,666, dated January 29, 1867.

IMPROVEMENT IN DEVICE FOR PREVENTING HORSES FROM CRIBBING.

The Schedule referred to in these Letters Patent and making part of the same.

TO ALL WHOM IT MAY CONCERN:

Be it known that we, ROBERT JENNINGS and JAMES A. MARSHALL, of Bordentown, in the county of Burlington, and State of New Jersey, have invented a new and improved Device to Prevent Horses from Cribbing; and do hereby declare that the following is a full, clear, and exact description thereof, reference being had to the accompanying drawings, forming part of this specification.

The nature of our invention has for its object a device to prevent horses from indulging in the habit disease of what is termed cribbing. It consists of two pieces of steel spring of suitable length, both made in the form of an arc of a circle, one within the other. The outer spring has a shorter or smaller diameter than the inner one. In the outside spring are secured several sharp points that project to near the inside spring. The inside spring is provided with a slot or mortise, through which these points project when the inner spring is pressed down.

To enable others skilled in the art to make and use our invention, we will proceed to describe its construction and operation.

Figure 1, a plan view of our device.

Figure 2 is a side elevation of the same.

Figure 3 is a sectional view from the line *xx*.

Letters of like name and kind indicate like parts in each of the figures.

A represents a spring, made of steel of suitable width and length, in the form of an arc of a circle. In the middle of this spring *A* are three or more steel points *a a a* firmly secured, which project out from the surface of the spring to a proper distance. At one end of the spring *A* is secured, by means of a pivot, *e*, an outer steel spring, *B*, of the same width as the spring *A*, but of greater diameter, so that the inside of the spring *B* do not come together, as a space is left between them, in the form of a crescent, and the space in which the points *a a a* occupy. At one end of the inside or shield spring *B* is a slot, *i*, that works over a button, *n*. In the middle of the inside spring is also another slot, *m*, through which the points project when the inside spring is pressed down. The ends of the outside spring *A* are perforated, so that the whole device can be secured to the throat-latch of the bridle or halter. It is secured so as to come upon the inside of the throat-latch immediately over the wind-pipe, so that as the horse begins to crib the wind-pipe expands in such a manner as to press the inside shield spring *B*, which causes the points *a* to protrude through the slot *m* in the spring *B*, and into the throat of the animal, when it will immediately desist any further attempt to crib. The habit or disease of cribbing is very detrimental and injurious to a horse, as it causes many to neglect their food, and has a tendency to emaciate and debilitate the animal. Our invention is a certain preventive to this injurious habit that is so common among the finest horses.

Having thus described our invention, what we claim as new, and desire to secure by Letters Patent,

1. The spring *A*, provided with the points *a a a*, to prevent horses cribbing, substantially as herein described, and for the purposes set forth.

2. We claim the inside shielding spring *B*, in combination with the spring *A*, substantially as shown described, and for the purposes set forth.

ROBERT JENNINGS,
JAMES A. MARSHALL
